U.S. Appl. No. 29/632,375, filed Jan. 8, 2018, Allowed.

Primary Examiner — T Chase Nelson*(74) Attorney, Agent, or Firm* — Quarles & Brady LLP**CLAIM**

The ornamental design for a shoe, as shown and described.

DESCRIPTION

FIG. 1 is a top, left, front perspective view of an ornamental design for a shoe;

FIG. 2 is a top, left, rear perspective view of the shoe of FIG. 1;

FIG. 3 is a front view of the shoe of FIG. 1;

FIG. 4 is a rear view of the shoe of FIG. 1;

FIG. 5 is a left side view of the shoe of FIG. 1;

FIG. 6 is a right side view of the shoe of FIG. 1;

FIG. 7 is a top view of the shoe of FIG. 1; and,

FIG. 8 is a bottom view of the shoe of FIG. 1.

The broken lines illustrate portions of the shoe that form no part of the claimed design.
